(57) **CLAIM**

The ornamental design for a wear plate for a trailer suspension hanger, as shown and described.

DESCRIPTION

FIG. 1 is a perspective view showing my design for a wear plate for a trailer suspension hanger;

FIG. 2 is a front elevation view thereof, the opposite side being a mirror image of FIG. 2;

FIG. 3 is a top plan view thereof;

FIG. 4 is a left side elevation view thereof;

FIG. 5 is a bottom plan view thereof; and,

FIG. 6 is a right side elevation view thereof.

The broken lines showing a trailer suspension hanger in FIG. 1 are illustrative of environmental structure only and form no part of the claimed design.
